UNITED STATES PATENT OFFICE.

JAMES MACPHAIL, OF BLUE ISLAND, ILLINOIS, ASSIGNOR TO THE PLANO MANUFACTURING COMPANY, OF CHICAGO, ILLINOIS.

DESIGN FOR A LINK.

SPECIFICATION forming part of Design No. 30,489, dated April 4, 1899.

Application filed March 9, 1899. Serial No. 708,452. Term of patent 14 years.

To all whom it may concern:

Be it known that I, JAMES MACPHAIL, a citizen of the United States, residing at Blue Island, in the county of Cook and State of Illinois, have invented and produced a new and original Design for Links for Driving-Chains, of which the following is a specification, reference being had to the accompanying drawings, showing a part thereof.

10 Figure 1 is a plan view of a link, showing my design. Fig. 2 is a side elevation of the same; and Fig. 3 is a cross-section on the line 3 3 of Fig. 2, these three views being deemed necessary to fully illustrate my design.

15 The leading feature of my design consists in the sides of the link, which have the narrow web, with a broadened curved flange thereon.

20 A is the cylindrical male bearing end of the link, while D is the hooked female bearing end, the hook proper, C, of which is slightly

less than the width of the rectangular opening in the center of the link. The sides D consist of the thin vertical web E, with the broadened curved flange F, the resulting cross-section of the sides being T-shaped and the flange F extending below the nose of the hook. The combined depth of the web E and the flange F at their point of junction with the cylindrical end A is considerably less than 30 the diameter of the end A and is just a trifle less than that of the mouth of the hook C. The ends of the cylindrical bearing portion A are beveled, as shown at G.

25 What I claim is—
35 The design for a link substantially as herein shown and described.

JAMES MACPHAIL.
